Attorney

UNITED STATES PATENT OFFICE

2,112,194

ROOFING AND SIDING MATERIAL

Norman P. Harshberger, Scarsdale, N. Y., assignor to Bakelite Building Products Co., Inc., New York, N. Y., a corporation of Delaware

Original application September 20, 1930, Serial No. 483,310. Patent No. 1,999,903, dated April 30, 1935. Divided and this application April 30, 1935, Serial No. 19,019.

12 Claims. (Cl. 108—7)

This invention relates to improvements in building material, particularly in prepared roofing materials including color or other surface ornamenting or protective additions and is a division 5 of my copending application Ser. No. 483,310, filed Sept. 20, 1930, now Patent No. 1,999,903, April 30, 1935.

It is one of the objects of this invention to provide composition material with designs or lines 10 of demarcation thereon for the purpose of creating an effect of a plurality of individual figures on a single element or strip.

A further object of this invention is to provide an improved building material made by the application to a traveling web of a quick-drying substance having the general drying characteristics of Duco, and as to the broad idea of the use 15 of cellulose material, such as Duco, this is described in my application Ser. No. 279,402, filed May 21, 1928, now Patent No. 1,900,861, March 20, 1933.

A more specific object of this invention is to provide mineral surfaced roofing elements having bands of weather resistant material over the 25 butt portions thereof to be exposed, for coloring and ornamental purposes.

A further object of this invention is to provide a roofing element having a quickly dried color coating over the exposed portions of the granular 30 particle facing thereof without affecting the texture of the granular particles and principally anchored to the base by said particles.

With the above and other objects in view, the invention consists of the improved article and 35 all its parts and combinations, as set forth in the claims, and all equivalents thereof.

In the accompanying drawing illustrating one embodiment of the preferred form of the invention, in which the same reference numerals designate the same parts in all of the views:

Fig. 1 is a vertical sectional view taken through the apparatus, parts being broken away, and the supporting frame for the various shafts being omitted inasmuch as this may be of any ordinary 45 construction;

Fig. 2 is a fragmentary plan view of the stencil belt;

Fig. 3 is a plan view of a portion of the cutting roller showing the arrangement of the knives 50 thereon;

Fig. 4 is a plan view showing one type of roofing element which may be formed by the improved method; and

Fig. 5 is a plan view showing an assembly of a 55 plurality of said elements.

Referring to the drawing, the numeral 8 designates a supporting roller which is rigidly mounted on a shaft 9. Said shaft may be journaled in any suitable bearings (not shown). Three other shafts 10, 11 and 12 are arranged in 5 triangular formation with respect to one another, and may also be journaled in a frame in the usual manner. Said shafts have mounted thereon stencil belt supporting rollers 13, 14 and 15, respectively. An endless stencil belt 16 is movable 10 around said rollers. For the purpose of removing any surplus paint from the stencil belt, yieldingly and pivotally mounted scrapers 17 may be employed which engage opposite sides of the belt.

At the right hand side of the roller 8, a supporting roller 18 is rotatably mounted, said roller being adapted to engage the lower side of the composition web 19. A printing roller 20, for a purpose to be hereinafter described, is mounted in vertical alignment with the roller 18 and is 20 adapted to engage the upper surface of the web 19. The printing roller 20 may be fed with ink or the like through the medium of an inking roll 21.

A cutting roller 22 is rotatably mounted beneath the web 19 and is engageable with the lower side thereof. Said roller is provided with knives 23 which are arranged in a desired form as shown in Fig. 3 to cut the web in a predetermined manner. A press roll 24 which is rotatably mounted above the web, is in vertical alignment with the cutting roller 22.

Beyond the roller 22 a table 25 is preferably provided for receiving the cut sections of material after said sections have left a cutting roll.

A pipe 26, or other suitable feeding device, having lower perforations 27 therein, and connected with a source of coloring material under pressure, is mounted between the rollers 13, 14 and 15 and is arranged to spray coloring material 40 through the rear of the stencil so that said material may pass through the apertures of the stencil to color the web along desired lines or in desired areas.

In carrying out the improved method, the main 45 supporting roll 8, the printing roll 20 and the cutting roll 22 are driven in any desired manner. An elongated sheet of roofing material, which comprises a fabric base coated with bituminous material and with a layer of granulated mineral, 50 is fed between the stencil belt 16 and a portion of the supporting roll 8. The rotation of the roll 8 will cause movement of the web and also movement of the stencil belt which is in frictional contact therewith. Coloring material 28 is 55

then applied through the medium of the feeding member 26 to the rear of said stencil, and said coloring material will pass through the apertures 29 of the stencil belt and will adhere to the web 5 below to create a design thereon.

If an ordinary paint or coloring material were employed, it would not be possible to perform the operations of cutting and stacking the cut elements without smearing of the coloring material.

10 For this reason, it is an important part of the method that a quick drying paint be utilized as the web of building material to which the quick drying paint is applied is usually quite hot after receiving its surfacing of interspersed mineral 15 particles and such will help drive off the volatile solvents of the paint and thereby bring about a rapid initial set. Said paint may be a cellulose mixture, as cellulose ester in a readily volatile solvent, commercially known as Duco, which possesses the property of drying very rapidly.

Inasmuch as the apertures 29 of the stencil belt must be separated at intervals as at 30 so that portions of the belt will not fall away, the lines of demarcation which will be applied to the 25 web will be broken at intervals. For this reason, the printing roller 20 is employed, said printer having a printing plate extending around its periphery which is formed to apply coloring material to the short sections of the web which are 30 below the portions 30 of the stencil belt. The web will therefore leave the printing roller with continuous lines of demarcation 31 thereon. Next, the web will be severed longitudinally and transversely by the knives 23 of the cutting roller 35 22 to produce from each side of the web a plurality of figured elements such as are shown in Figure 4.

Each of said elements is then cut inwardly from its lower edge as at 32 to form a slit for engagement with a lug 33. The shingles produced may 40 be laid as shown in Figure 5 with adjacent elements in the same row having overlapping ends which are interlocked through the lugs and slits 33 and 32, and with the lower edge of one row above overlapping the upper edge of a row below, 45 as shown in Figure 5, to create an effect of a plurality of brick-like figures.

Although the coloring material 28 is shown as applied in the form of a spray, it may also be applied by a soft application roll, or in any other 50 suitable manner. It is further to be understood that the stencil may be formed to produce any type of design on the web, the brick-like design shown being merely for the purpose of illustration. All other changes and modifications are 55 also contemplated as may come within the scope of the claims.

I claim:

1. As an article of manufacture, a colored shingle element comprising a water resistant 60 flexible base, a granular surface roughening material adhesively secured to said base, and a hardened and weather-resistant colored coating secured to the exposed surface of said granular material, said coating comprising a substantially water-insoluble quick drying lacquer.

2. An ornamental shingle element comprising a base, a surface roughening material comprising mineral particles adhesively secured to said base and a colored coating comprising a hardened 70 and weather-resistant film comprising a substantially water-insoluble quick drying coating secured to the exposed surface of said mineral particles and adhesive, said particles acting as a means of bonding said coating to said base.

75 3. As articles of manufacture flexible shingle

elements each comprising a fibrous base, a bituminous layer, mineral particles interspersed and partially embedded in said layer, and a hardened weather-resistant color surfacing comprising a substantially water-insoluble quick drying film over said mineral particles, said mineral particles acting as the principal means of bond for said surface coating and said shingle elements being adapted to be stacked during manufacture without smearing their surfacing.

4. As articles of manufacture ornamented flexible shingle elements comprising mineral surfaced fibrous bases having thereon continuous colored bands of a hardened weather-resistant coating anchored by said mineral surfacing in 1 position, said coating comprising a substantially water insoluble quick drying lacquer.

5. As articles of manufacture ornamented flexible shingle elements comprising mineral surfaced fibrous bases having thereon continuous 2 colored bands of a hardened coating anchored by and covering the exposed portions of said mineral surfacing said coating comprising a quick drying cellulosic ester lacquer.

6. As an article of manufacture, a colored shingle element comprising a water resistant flexible base, a granular surface roughening material adhesively secured to said base and partially embedded therein, and a colored coating comprising the dried residuum of a quick drying cellulose ester lacquer over the exposed portions of said particles and anchored thereto, said granular surfacing acting as the principal means of bond for said colored coating.

7. An ornamental shingle element comprising 35 a base, a surface roughening material comprising mineral particles adhesively secured to said base and partially embedded therein and a hardened weather resistant colored coating comprising a quick drying cellulose ester lacquer over 40 said base and exposed mineral particles and without affecting the texture of said particles, said particles acting as a means of bonding said coating to said base.

8. As articles of manufacture flexible shingle 45 elements each comprising a fibrous base, a bituminous layer, mineral particles interspersed and partially embedded in said layer, and a hardened weather resistant color surfacing comprising a substantially water-insoluble coating having quick 50 drying characteristics covering the exposed portion of said particles and the bituminous layer therebetween to protect the same, said mineral particles acting as the principal means of bond for said surface coating, and said shingle elements being adapted to be stacked during manufacture without smearing their surfacing.

9. As an article of manufacture, a colored flexible shingle element comprising a composition base layer, mineral particles partially anchored in said 60 base layer, there being another surface coating on the exposed surface of said particles comprising a quickly set cellulose ester lacquer and bonded by the mineral particles to said base.

10. An ornamental shingle element comprising 65 a base, a surface roughening material comprising mineral particles adhesively secured to said base and partially embedded therein, and a hardened and weather-resistant film comprising a substantially water-insoluble quick drying 70 lacquer coating over the exposed mineral particles, and base portion in the interstices therebetween, and presenting the texture of the mineral particles.

11. As an article of manufacture, roofing com- 75

prising a base, a bituminous layer on said base, a layer of individual granules embedded in said bitumen, and a hardened and weather-resistant coating anchored to said granules on the portion exposed above the bitumen layer and without affecting the exposed surface contour of said granules, said coating comprising a substantially water-insoluble quick drying coating composition including a synthetic base.

12. As an article of manufacture, roofing comprising a base, a bituminous layer on said base, a layer of individual granules embedded in said

bitumen, and a hardened and weather-resistant coating anchored to said granules on the portion exposed above the bitumen layer and without affecting the exposed surface contour of said granules, said coating comprising a substantially water-insoluble quick drying coating composition including a synthetic base, and said coating being on only a portion of said roofing to be exposed whereby to create an ornamental visual effect by the contrast between the coated and uncoated portions to be exposed. 5 10

NORMAN P. HARSHBERGER.
